UNITED STATES PATENT OFFICE

2,561,813

FRAME FOR LETTER BLOCKS

Joseph F. Murphy, West Roxbury, Mass., assignor
of one-half to Edward F. Murphy, Jamaica
Plain, Mass.

Application September 23, 1948, Serial No. 50,828

1 Claim. (Cl. 40—140)

1

This invention relates to the printing industry and comprises a new and improved outfit or system for assembling body type in high grade proofs for display headings, layouts, off-set printing, ads, zincs and the like.

Heretofore such proofs have usually been produced from type that must be set by hand at considerable expense and with a very limited range of available styles. This is because fonts of large sized type are costly and the printer's equipment does not include many variations. Moreover, the employment of body type is expensive because the proof usually requires retouching to eliminate pin holes or other blemishes where the ink has failed to produce a solid black impression. Further, the work requires the services of an experienced type setter since such body type appears in the reverse of its impression.

The outfit of the present invention overcomes these disadvantages, increases the printer's resources, reduces the cost of body type work and produces a superior proof by a photographic process. By the procedure of my invention a great amount of space is saved which under the old system is required for storing foundry type. It also eliminates inking and furniture heretofore required. It contemplates the use of blocks having transparent type therein and these take up so little space that it is possible for the small printer to compete with larger operators.

Going more into detail, my novel outfit includes a frame having side and end members together with a series of guide bars, the end members and the guide bars being shaped for detachable interlocking at both ends or sides of the frame. Preferably and as herein shown, the guide bars present projecting shoulders and the type blocks are supported on said shoulders in flush relation. The type blocks may be transparent and carry an opaque negative in which a transparent letter is outlined or, if preferred, the letters may be opaque in a transparent block. The blocks may be readily and accurately placed in the desired relation and, as assembled, they are viewed directly as their impression is to be seen and not in reverse as in the case of ordinary type. The individual blocks are so located and fitted together that they form with the frame a light-tight mat about the transparent outline of the letters. Having once assembled the individual type blocks, the frame and letters may be placed in a photographer's enlarger and the line of type photographed directly onto a sensitized surface. In this manner a proof may be formed with the letters enlarged or reduced to any desired size.

2

A feature of the present invention consists in a series of shouldered guide bars having a projecting rib or flange at each end in combination with a frame having end or side members divided by uniform notches into which the projecting rib of the guide bars may be detachably fitted in position to receive type blocks of predetermined dimensions and to properly locate the line to be printed.

10 Another feature of the invention consists in a series of type blocks having shoulders arranged to interlock and thus form a continuous screen within the confines of the frame.

15 These and other features of the invention will be best understood and appreciated from the following description of a preferred embodiment thereof, selected for purposes of illustration and shown in the accompanying drawings, in which:

20 Fig. 1 is a plan view of the outfit in partially assembled position,

Fig. 2 is a view in longitudinal section on the line 2—2 of Fig. 1,

Fig. 3 is a cross-sectional view on the line 3—3 of Fig. 1,

Fig. 4 is a view in longitudinal section on the line 4—4 of Fig. 1, and

Fig. 5 is a fragmentary view in perspective showing parts of the frame and type blocks in exploded relation.

25 In Figs. 1 and 2 the slide or frame 10 of a commercial enlarging camera is outlined in dot-and-dash lines. The assembly device of my invention may be used in association with such a frame, or it may be made to fit into any photographic contact printer. The advantage of using it in an enlarger is that the size of the type letters may be conveniently enlarged or reduced in the process if desired, whereas in contact printing the impression reproduces the actual size of the type.

30 The frame 10 is provided with a rectangular shouldered recess of the proper size and shape to support and enclose a smaller frame comprising side members 12 and 13 and notched end members 14 and 15. The side and end members of the frame are shaped to interlock at the corners and are held together by screws, as suggested in Fig. 5. The frame 10 is also provided with clips or latches 11 which may be swung over the end members of the smaller frame and hold the latter securely in position. The end member 14 is formed with a continuous ledge or shoulder 16 underlying a series of spaced rectangular projections providing square-sided notches and pro-

jecting inwardly into the frame beyond the projections, and the end member 15 is similarly shaped. The upper portion of the end member 15 is also formed with a series of similar projections providing uniform transverse notches 17 corresponding in location to those of the end member 14. Detachably retained within the frame is a series of guide bars 18 presenting continuous shoulders on both sides underlying an upstanding median rib 19. The rib 19 extends beyond both ends of the shoulders of the bar in which it is formed and is shaped to fit snugly within the notches 17 of the end members 14 and 15 and to lie flush with the upper surface of the notched portions of the bars. The underlying shoulders of the bars are located in the same plane as the underlying shoulders of the end members and the side members of the frame.

Type blocks 20 of preferred form are best shown in Fig. 5. The blocks are rectangular, shouldered on one side and undercut on the other so as to make flush interlocking engagement. In thickness the blocks correspond to the height of the rib 19 of the guide bars and of the portions of the end and side members located above their underlying shoulders. Accordingly, regardless of the position of any type blocks, their upper surface will form a common plane with the walls of the frame. As herein shown the upper and one side face of each block is covered with an opaque negative, indicated in Fig. 5 by stippling, in which is formed a transparent letter. In dimensions the type blocks are formed to be positioned by guide bars located in the frame with one or more notches between them; for example, the type blocks 20 shown in Fig. 1 are located at their ends by guide bars 18 having three notches between them, and the smaller type blocks 21 are located between guide bars having a single notch between them.

It is important that the type blocks be assembled to form a complete opaque screen through which light may pass only in the transparent outline of the type letters. Accordingly, the type blocks are individually shouldered and grooved as shown in Fig. 5 to make interlocking engagement at their longitudinal edges as shown in Fig. 4. The presentation of a continuous dark screen is thus insured.

As suggested in Fig. 1, the type blocks may be supported between two adjacent guide bars 18 or between a guide bar and one of the side members 12 or 13 of the frame. It will be seen also that the side edges of any type block are supported by the underlying shoulders of the end

members 14 and 15 as shown in Fig. 4, this providing a tight and compact assembly.

As suggested in Fig. 3 the type blocks are of laminated construction with the negative 22 in which the letter is formed interleaved between them and thus protected on both sides against scratching or contact with oil. The life of the type blocks is therefore prolonged and the shape outline of the letter safeguarded.

The shoulders of the type blocks are so proportioned that the blocks lock together and give the proper spacing between adjacent letters. The separation indicated in Fig. 5 is somewhat exaggerated for illustrative purposes. The blocks in all cases are stiff self-contained units whether they are of laminated form as shown in Fig. 3 or of integral configuration as shown in Figs. 4 and 5.

Having thus disclosed my invention and described in detail an illustrative embodiment thereof, I claim as new and desire to secure by Letters Patent:

A device for supporting letter blocks comprising an open frame having end members, each of said end members having an inwardly projecting shoulder and a plurality of projections extending upwardly of said shoulder, said projections forming grooves therebetween, a series of guide bars having side and end portions, shoulders on each side portion, a tongue protruding from the ends of each guide bar and extending into one of said grooves in flush relation therewith, and a row of indicia blocks supported in flush relation on the shoulders of two adjacent guide bars, said blocks having interlock portions whereby they are in interlocking engagement with one another, the interlock portion of each end block of each row overlapping and resting on the shoulder of one of said end members whereby light is excluded between the blocks and also between the blocks and frame.
